UNITED STATES PATENT OFFICE.

FRANK SCHWARZ, OF McCLEARY, WASHINGTON.

LAUNDRY DEVICE.

1,293,212.

Specification of Letters Patent.

Patented Feb. 4, 1919.

Application filed July 29, 1918. Serial No. 247,281.

To all whom it may concern:

Be it known that I, FRANK SCHWARZ, a citizen of the United States, residing at McCleary, in the county of Grays Harbor and State of Washington, have invented 5 certain new and useful Improvements in Laundry Devices; and I do declare the following to be a full, clear, and exact description of the invention, such as will enable others skilled in the art to which it 10 pertains to make and use the same.

This invention relates to laundrying devices, and it relates more specifically to an improved form of clothes-stick.

15 One of the objects of this invention is to provide a device of this character which will effectively and quickly engage with the clothes in a tub or boiler for lifting them therefrom or stirring and shifting them to 20 facilitate the washing thereof, without danger of tearing or otherwise injuring the clothes.

Another object is to provide a device of 25 this character that may be manipulated with comparative ease; and

Another object is to provide a device of this character which may be manufactured at a comparatively low cost.

Other objects and advantages may be 30 apparent to persons who read the following details of description in connection with the accompanying drawings in which:—

Figure 1 is a side elevation of my improved clothes-stick;

35 Fig. 2 is a transverse sectional view along the line 2—2 of Fig. 1; and

Fig. 3 is a transverse sectional view along the line 3—3 of Fig. 1.

Referring to these drawings in detail in 40 which similar reference characters correspond with similar parts throughout the several views, the device is preferably turned integrally from a piece of hard wood and then formed with V-shaped grooves which 45 extend along the stick, so that a plurality of annular series of lateral projections are formed at one end portion of the stick; the other end of the stick, as well as its intermediate portion, being smooth and cylindrical 50 cal so as to provide a handle or manipulating element. The handle is designated by

the reference character 5, and is approximately four times as long as the clothes-engaging portion 6 which is formed by the said plurality of annular series of lateral 55 projections. The projections are indicated by the reference character 7, and those of each annular series are separated from one another by the V-shaped grooves 8. Each annular series forms a group which is substantially frusto-conical and which tapers toward the clothes-engaging end of the stick. In other words, each lateral projection 7 has a convex surface which diverges from a line extending longitudinally through 60 the center of the stick, the direction of divergence being toward the handle 5. By cutting the V-shaped grooves 8 transversely of the annular grooves which separate the annular series of elements 7 from one another, each of these elements 7 is formed with a pyramidal apex 9 at each of its opposite sides, or at each side of the adjacent grooves 8. The apexes or points 9 are somewhat sharp, so that an article of clothing 65 may be engaged therein upon imparting a rotary motion to the stick while in engagement with the clothing; but the points 9 are not so sharp as to injure the clothing because they are formed by the meeting of 70 75 the apexes of three obtuse-angular surfaces.

The manipulation of this device will be understood and appreciated by persons who are familiar with the art of laundrying.

Although I have described this embodiment of my invention very specifically it is not intended to limit the same to these exact details of construction, but I am entitled to make changes within the scope of the inventive idea disclosed in the foregoing description and the following claim.

What I claim as my invention is:

A clothes-stick comprising a clothes-engaging portion formed with a plurality of annular series of lateral projections, each of 95 said projections terminating in a sharp corner which is formed by the meeting apexes of three obtuse angles that form surfaces of the projection.

In testimony whereof I have hereunto set 100 my hand.

FRANK SCHWARZ.
